ELMER E. SPEER, OF BALLSTON, VIRGINIA, ASSIGNOR TO GABRIEL EDMONSTON, OF WASHINGTON, DISTRICT OF COLUMBIA.

BINDING DEVICE FOR MOLDS, &c.

1,268,061.

Specification of Letters Patent.

Patented May 28, 1918.

Application filed August 17, 1916. Serial No. 115,491.

To all whom it may concern:

Be it known that I, ELMER E. SPEER, a citizen of the United States, and a resident of Ballston, in the county of Alexandria and 5 State of Virginia, have invented Binding Devices for Molds, &c., of which the following is a full and complete specification.

My invention is an improvement in molds or casings used in forming concrete supporting columns, and relates more especially to the means employed for connecting the parts 10 of the mold or casing together to receive the concrete.

In concrete work of this kind it is customary to construct the mold or casing of several parts which are fitted together and connected usually by means of metal binding straps or bands drawn tightly around the mold, the ends of said binding strap or band 15 being securely held in locked engagement with a clamping device or keeper, whereby after the concrete has been poured and becomes set the parts of the mold may be unbound, separated and removed.

25 The clamping devices or keepers heretofore used in this connection require one or both ends of the strap to be specially formed, and in some instances the implement for drawing the band taut about the mold remains as a permanent part of the holding 30 device or keeper.

The primary object of my invention is to provide an inexpensive sheet metal device to primarily hold the respective ends of the 35 band or binding strap by frictional engagement and adapted for use in connection with a pulling implement for drawing the band or strap tightly around the mold; all as hereinafter fully described and specifically 40 set forth in the appended claims.

In the accompanying drawings, which form a part of this specification:

Figure 1 is a front elevation illustrating the application of my invention in connection 45 with a mold for forming a concrete column.

Fig. 2 is a sectional view through the front portion of the mold to show a side view of the sheet metal clamping device 50 or keeper.

Fig. 3 is an enlarged sectional view through the clamping device or keeper and showing the application of the pulling implement.

55 Fig. 4 is a transverse sectional view

through the clamping device or keeper, on the line 4—4 of Fig. 3.

Like numerals of reference indicate like parts in all the figures of the drawings.

In the drawings I have illustrated my invention as applied for the purpose of connecting together the parts of a mold used in forming a concrete supporting column, but it will be understood, of course, that the devices hereinafter particularly described may 60 be conveniently employed in other situations wherever it is desired to clamp and hold a metal band or strap about a structure of any kind. In the present instance, however, I have shown the mold as consisting of four 65 sides, 7, each provided with a projecting rib, 7^a, to form a continuous curved surface to facilitate the operation of drawing or binding the strap or band 8 around the mold, several sets of ribs being used and spaced 70 a short distance apart to provide a strong and substantial mold structure. On the other hand, when the devices are used in connection with a round mold or structure the projecting ribs will be unnecessary inasmuch as the parts of the mold when assembled will present a round contour.

The keeper device is preferably made from a sheet metal plate stamped or otherwise formed U-shape in cross-section to present a bottom part 9 and opposite longitudinal side walls, 10, 10, the whole structure being slightly curved longitudinally to approximate the curve of the surface with which it is adapted to be used. Mounted 85 between the side walls at one end of the device is a cam 11, having gudgeons 12 and 13 working in apertures therefor in the side pieces and disposed with reference to the bottom of the keeper so that the cam may 90 clamp an end of the binding strap or band between it and said bottom, and in order to insure an effective grip the engaging surfaces of both the cam and bottom of the keeper are preferably roughened or serrated 95 transversely, as indicated in Fig. 3 of the drawings. This cam engages and holds one end of the binding strap or band 8, and in order to hold the other end of said strap or band a similar cam, 14, having gudgeons 15

100 and 16, is located near the other end of the keeper. It will be noted that the arrangement of each cam is such that it will impinge against the strap or band when said cam swings outwardly or toward the end 110

of the keeper; whereby the greater the pull on the binding strap, in the direction of strain, after it has been tightened around the mold, the more tightly the cam will hold.

5 One of the gudgeons of each cam is squared at its end to receive an ordinary nut-wrench for the purpose of turning said cam in clamping the same on the band and releasing it, and in order to limit the throw of the 10 cam inwardly lugs 10^a, 10^a are struck from the opposite side walls to project in the path of the enlarged portion of said cam. The metal keeper is of such length that the cams are spaced a sufficient distance apart to permit 15 of the operation therebetween of a pulling implement, hereinafter described, which is adapted to fit between the side pieces or walls 10, 10, and bear in recesses or depressions 7^a in the outer edges thereof.

20 The pulling implement consists of a head or casting 18, of a width slightly less than the space between the side pieces of the keeper and having opposite trunnions 19 which seat in the recesses or depressions 17, 25 said head or casting being also provided with projecting ears or members 20, 20, to receive the other part of the implement, or lever 21, having a cam-surface 21^a coöperating with a flattened inner surface of the 30 head to clamp the free end of the binding- strap or band 8 in the implement.

From the foregoing description, in connection with the accompanying drawings, the operation of the device will be readily 35 understood; for after the parts of the mold are assembled the band 8 is placed around the same at the center of the alining ribs 7^a, and one end of the band connected securely to the keeper by being passed under the 40 cam 11 and the latter turned by a wrench to engage said band. The other end of the binding strap or band is then passed under the other cam of the keeper and threaded through the pulling implement between the head 18 and cam-end 21^a thereof, and after 45 said pulling implement is slipped into the bearing recesses 17 of the keeper it is moved forward to obtain a grip on the loose end of the band near to the cam, and then pulled rearward to draw upon the band in tightening 50 the same around the mold. This operation of moving the pulling implement forward and backward is repeated until the band is drawn taut, and this end of the band is then securely locked in connection with 55 the keeper by moving the cam 14 into engagement therewith by the use of a wrench. The pulling implement is now removed, the ends of the band being securely connected by locked engagement with the keeper to hold the said band tightly and firmly bound around the parts of the mold. Of 60 course several bands are placed around the mold, being spaced apart the desired distance to provide a mold-structure of the re-

quired strength to withstand the pressure of the wet cement mixture or other plastic composition.

If the mold should loosen up from any cause during the pouring of the mixture 70 therein, said mold may be tightened at any point without releasing any of the bands preliminary to the operation of further tightening the same; for in this instance the pulling implement is applied to the loose 75 end of the band to be tightened and after said implement is fulcrumed in the keeper and a firm hold obtained on said band the engaging cam, 14, may be eased up until the band is tightened and then moved into 80 engagement; in other words, it is not required to permit any further slack in the band, with possible disastrous results, when it is desired to tighten the band and mold.

As the pulling implement is removable 85 after performing the operation of tightening the band around the mold, it is not a permanent part of the keeper or connection for the ends of the band, thereby presenting a connection which is simple, cheap and compact in construction. Furthermore, a single 90 pulling implement may be used in connection with any number of keepers, and therefore the keepers may be sold separately.

As will be noted, the ends of the band do 95 not have to be specially formed but simply extend under and beyond the cams; and the pulling implement being reversible with respect to the cams may be used in connection with either end of the said band, permitting 100 the pulling implement to be used alternately on first one end and then the other to effect a closer binding together of the parts of the mold.

I purpose making the keeper plate of sheet 105 steel, and in this instance the serrated portions of the bottom thereof, immediately below the cams, may be suitably hardened to reduce the wear and secure a better hold on the end portions of the binding strap 110 or band.

By providing the lugs 10^a they limit the throw of the cams so that they will not interfere with the operation of threading the 115 ends of the band through the keeper device by swinging all the way around and engaging the band toward the end of the keeper.

Though I have described my invention as particularly adapted for the purpose of binding the parts of a mold together it will 120 be understood, of course, that it may be employed for various other purposes; for instance to bind a water tank, cistern, &c.

Having described my invention, I claim:

1. A device for binding molds, &c., comprising a band, a metal keeper for connecting the ends of the band, said keeper being U-shaped in cross-section and having alining apertures in its side walls near the opposite ends thereof, cams rotatably mounted 125

130

in said apertures to co-act with a part of the keeper to clamp the ends of the band therein, means for tightening said band around the mold, and means carried by one of the 5 cams to provide for manually turning the same.

2. A device for binding molds, &c., comprising a band, a metal keeper U-shape in cross-section, means for connecting the band 10 to one end of said keeper, and a cam rotatably mounted in the other end of said keeper between the side walls to co-act with a part of said keeper to clamp and hold the other end of the band, an end of the cam projecting beyond the adjacent side wall to receive a wrench.
3. A device for binding molds, &c., comprising a band, a metal keeper U-shape in cross-section, means for connecting the band 20 to one end of said keeper, a cam rotatably mounted in the other end of said keeper to co-act with a part thereof to clamp and hold the other end of the band, and means for tightening the band around the mold.
- 25 4. A device for binding molds, &c., comprising a band, a metal keeper U-shape in

cross-section, means for connecting the band to one end of the keeper, a cam rotatably mounted in the other end of said keeper to co-act with the bottom thereof to clamp and hold the other end of the band, and a lug 30 projecting from a side wall of the keeper to limit the throw of the cam in one direction; together with means for tightening the band around the mold.

35 5. A device for binding molds, &c., comprising a band, a metal keeper U-shape in cross-section, means for connecting the band to one end of the keeper, a cam mounted in the other end of said keeper to co-act with 40 the bottom thereof to clamp and hold the other end of the band, said cam having an end thereof projecting beyond the adjacent side wall and squared to receive a wrench, and a lug struck from a side wall of the 45 keeper to limit the throw of the cam in one direction; together with means for tightening the band around the mold.

ELMER E. SPEER.
